REFLECTOR

Gustav Dietz, West Hollywood, Calif.

Application December 21, 1936, Serial No. 117,025

1 Claim. (Cl. 240—41.36)

This invention relates generally to lamp reflectors, and more particularly to an improved type of reflector for an airplane landing light having an incandescent lamp as the source of light.

Ordinary reflectors produce a light of either the "spot" type or of the "flood" type. The spot light producing reflector is objectionable in that it puts too much light in a small area, and consequently is not suitable for use as landing light equipment on airplanes. On the other hand, the flood light reflector spreads the light to such an extent horizontally that the resulting light is too greatly diffused and is not capable of giving sufficient illumination directly in the path of a landing airplane.

In view of these objectionable features, it is a primary object of this invention to provide a reflector for an airplane landing light which will combine the best qualities of the spot type and flood type lights in order to produce a desired distribution of light over the ground from the immediate foreground to a considerable distance with desired spread, and having an increased intensity of illumination horizontally directly in the path of the airplane as it approaches the ground to make a landing.

It is a particular object of this invention to provide a reflector that will produce simultaneously a circular beam of light and a horizontal light beam cutting across and extending laterally beyond the circular beam, the horizontal light beam being of greater strength than the circular beam. It is a further object of this invention to provide a reflector of the type described, by dividing its reflecting surface into four major reflecting sections or areas, each section having a plurality of reflecting surfaces, the opposite sections cooperating to produce desired types of light beams. Finally, it is a further object of this invention to provide a reflector of the type described which is accurate and efficient and is of durable construction.

These objects are achieved in the construction shown in the accompanying drawing, in which

Fig. 1 is a front elevation of the reflector.

Fig. 2 is a sectional elevation on line 2—2 of Fig. 1.

Fig. 3 is a fragmentary plan view of a reflecting segment used for producing the circular light beam.

Fig. 4 is a plan view showing in diagrammatic form the shape of the light beams produced by the reflector.

Fig. 5 is a cross section of the light beam taken on line 5—5 of Fig. 6.

Fig. 6 is a diagrammatic view, showing the manner in which the light beams hit the ground when an airplane is approaching the ground to land.

Referring more particularly to the drawing, reference numeral 11 indicates a shell, or base, preferably of spun aluminum having a socket portion 12 adapted to receive a lamp socket (not shown). In the socket portion is mounted a ring 13, having a flange 14.

The reflector has a composite reflecting surface which is divided into four major reflecting sections, designated by the letters A, B, C, and D. Each of these sections has a plurality of reflecting surfaces formed upon reflecting segments which will subsequently be described in detail. The opposite vertical sections A and B cooperate to produce a circular beam of light 20 in cross-section, while the opposite horizontal sections C and D cooperate to produce a flat beam of light which transversely cuts the circular beam.

Preferably these sections are so formed that the width of the sections at their outer ends as measured on the periphery 23 (formed by the outer edge of the reflecting segments) is greater for the sections A and B than it is for the sections C and D. Thus, the distance from point 21 to point 15 of section A on the periphery 23, and the corresponding distance from point 19 to point 17 of the section B is greater than the distance from point 21 to point 19 of section C or the distance from point 15 to point 17 of section D. These distances 21—15 and 19—17 are each greater than one-fourth of the distance around the periphery 23, while the distances 21—19 and 15—17 are each less than one-fourth of the distance around the periphery 23. However, the sections A and B converge more toward the center of the reflector than the sections C and D, so that the width of the sections A and B at their inner ends, as measured around the flange 14 of ring 13, is less than that of the sections C and D. Thus, the distances from point 22 to point 16 and point 20 to point 18 are less than the distances from point 22 to point 20 and point 16 to point 18 around the periphery 50 of flange 14. The distances 22—16 and 20—18 are each less than one-fourth of the distance around the flange 14 while distances 22—20 and 16—18 are each more than one-fourth the distance around flange 14. However, the shape and 55

size of the areas might be varied somewhat without departing from the scope of the invention.

In the sections A and B, reflecting segments 25, which have converging sides 26 and 27, form the reflecting bodies. These segments are made of flexible metal strips, having a suitable reflecting surface applied to them. The strips are flat from side to side and have a slightly broken surface indicated by the line 28. When mounted in 10 the reflector, each segment has a straight flat surface from side to side, that is, on any line at right angles to the longitudinal axis of the segment and on the surface plane of the segment at that point. Longitudinally each segment is 15 curved corresponding to the curve of the inner surface of the shell 11. However, due to the "breaks" in the reflecting surface indicated by numerals 28, the reflecting surface is not a true curve, but may be described as substantially 20 curved. These segments are held in place at their inner end by the flange 14 under which they fit, and at their outer end by screws 29 which engage notches 25' of segments 25 (Fig. 3) and through the shell 11, nuts (not shown) 25 engaging the outer ends of the screws. In order to fit into the curved inner surface of the shell 11, the segments 25 have one side slightly convexly curved and one straight side. But for 30 the one slightly curved side of these members, they would be trapezium-shaped.

The longitudinal axes of the middle segments in each of the sections A and B are radially disposed in the shell 11 while the other segments 25 from the middle of the sections outward to 35 the side are each increasingly inclined with relation to radial lines extending outwardly from the center of the reflector. The sections C and D have reflector segments 33 which are likewise made of strips of metal, each having a reflecting 40 surface. The inner side 34 of each of these segments is convexly curved, except the innermost one in each section, which is cut concavely to fit over ring 13, and under its flange 14, while the outer side of each is straight (with the exception 45 of the outer one on each area which is curved to produce the curved outer boundaries of the section). The ends of the segments 33 are cut at an angle as indicated in order that they may fit into and form the sections C and D which 50 converge toward the center of the reflector, as disclosed in Fig. 1. Thus each segment is of less length than its neighboring outward segment. The segments (except the two inner ones which are cut away to fit around the ring 13) 55 are substantially trapezoidal in shape and could be thus defined were it not for the one curved side of each. Mounted in the reflector each segment has a straight flat surface from side to side on any line at right angles to the longitudinal 60 axis of the segment and on the surface plane of the segment at that point. Longitudinally each segment is curved corresponding to the curve of the inner surface of the shell 11, however, due to the formation of the reflecting surface with "breaks" therein, the reflecting surface is not a true curve and can only be described as substantially a curved surface. These segments are also held in place by means of screws, here indicated as 35, which extend through holes 65 in the base 11, and have nuts on the outer side of the base 11. The segments have their longitudinal axes vertically disposed in the reflector. 70

The segments 33 in the sections C and D produce the flat wide beam above referred to, and 75 by reason of the fact that they have a broken

surface, they reflect a light free from images, and of even quality. The segments 25 in the opposite vertical sections A and B produce the circular light referred to above. The reason for dividing the sections A, B, C, and D into a plurality of slightly broken reflecting surfaces is to provide a smooth even light without dark spots. 5

Although the opposite vertical sections A and B have been shown and described as comprising a plurality of reflecting segments 25, it is 10 within the scope of this invention to form each of these reflecting sections A and B with a plain, unbroken reflecting surface and not use a plurality of reflecting surfaces. Thus, each of the sections A and B might comprise merely a single 15 reflecting surface. This would produce a circular beam smaller in diameter than that produced by a device having a plurality of reflecting surfaces, but it would give a stronger light.

In Fig. 4 there is diagrammatically illustrated 20 a plan view of a light produced by the reflector. The beam indicated by reference numeral 40 is the beam circular in cross-section produced by the vertical opposite sections A and B. Superimposed across the middle of this beam and extending beyond it and spreading outwardly is the beam 41, produced by the horizontal sections C and D.

Fig. 6 shows diagrammatically the way in which the light beam intersects the ground when an 30 airplane is approaching the ground to make a landing. Here an airplane wing 42 is diagrammatically shown, which has mounted thereon a landing light 43 having embodied therein a reflector of the type herein described. Reference 35 numeral 40 indicates the circular beam produced by the opposite vertical sections A and B of the reflector and 41 indicates the flat beam. From this it can be seen that the reflector produces a desirable spread of light over the ground 40 giving illumination from the immediate foreground to a distance of 2,000 feet or more.

Fig. 5 is an enlarged cross-section of the light taken on line 5-5 of Fig. 6. It clearly illustrates the manner in which the flat beam 45 intersects and is superimposed upon the circular beam.

Although the invention has been illustrated and described in a particular manner and the reflecting segments have been described to be of particular shape, it is not essential to this invention that they be exactly so shaped. Neither is it essential to the invention that the sections A and B, and C and D be shaped exactly as described and illustrated or in the exact proportions described, but it is within the scope of this 55 invention to vary the relative dimensions of the sections and the reflecting segments.

I claim as my invention:

A reflector comprising: a shell having a centrally disposed lamp socket opening; a ring member mounted in said opening, said ring having a flange thereon extending beyond said opening at the inner end thereof; a plurality of reflecting segments having converging sides and being of equal width substantially radially mounted in 60 said shell and forming oppositely disposed reflecting areas; the inner ends of said members extending under said flange of said ring, the outer ends of said members being individually secured to said shell by means of screws; and a plurality 65 of vertically extending reflecting members mounted in said shell to form oppositely disposed reflecting areas; said members being individually secured to said shell by means of screws.
